COMBINATION COCKTAIL SHAKER, HUMIDIFIER
AND CANISTER OR THE LIKE

Peter Schlumbohm, 41 Murray St., New York, N.Y.

Filed Mar. 28, 1960, Ser. No. 59,899

Term of patent 14 years

(Cl. D2—3)

FIG. 5

FIG. 2

FIG. 1

FIG. 4

FIG. 3

Fig. 1 is a side elevational view of a combination cocktail shaker, humidifier and canister or the like, showing my new design;

Fig. 2 is a bottom plan view thereof;

Fig. 3 is a perspective view thereof;

Fig. 4 is a perspective view of a modified form thereof; and

Fig. 5 is a perspective view of another modified form thereof.

I claim:

The ornamental design for a combination cocktail shaker, humidifier and canister or the like, as shown.
